CLAIM

The ornamental design for a brewing device as shown and described.

DESCRIPTION

FIG. 1 is a perspective view of a brewing device showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is perspective view of the brewing device, showing the brewing device's pitcher separately for ease of illustration;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is perspective view of the brewing device, showing the brewing device's base separately for ease of illustration;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The broken lines show environment that forms no part of the claimed design. The dot dash broken lines show boundaries of the claim and form no part of the claimed design.

1 Claim, 19 Drawing Sheets
